UNITED STATES PATENT OFFICE.

ERNST G. K. ANDERSON, OF CHICAGO, ILLINOIS, ASSIGNEE TO ANDERSON ELECTRIC & EQUIPMENT COMPANY, OF CHICAGO, ILLINOIS, A CORPORATION OF ILLINOIS.

ELECTRIC SWITCH.

1,403,222.

Specification of Letters Patent. Patented Jan. 10, 1922.

Application filed December 23, 1920. Serial No. 422,861.

To all whom it may concern:

Be it known that I, ERNST G. K. ANDERSON, a citizen of the United States, and a resident of Chicago, in the county of Cook 5 and State of Illinois, have invented certain new and useful Improvements in Electric Switches; and I do hereby declare that the following is a full, clear, and exact description thereof, reference being had to the accompanying drawings, and to the characters of reference marked thereon, which form a part of this specification.

This invention relates to improvements in electric switches and refers more particularly to a novel so-called one-way switch in which the actuator or lever has movement in one plane to actuate a snap switch to open or close a circuit, the movable switch element remaining in position to which it 20 has been thrown and the lever returned to normal after each actuation, to be in position upon the next operation of the lever or actuator to throw the snap switch to another position.

My improvements may be applied to different kinds of machines or apparatus, and is especially adaptable for machines or apparatus in which the location of the valve is necessarily or preferably such as to be 25 inconvenient to be operated by hand, but adapted to be operated by foot pressure. One example of my invention, as shown in the accompanying drawings, is in its application to a vacuum cleaning machine where- 30 in the motor which drives the cleaning element of the machine is located adjacent to the floor. In such a use it is convenient and desirable to place the switch adjacent to the motor and to support it thereat, and 40 the most convenient manner of operating the switch is by foot power.

The purpose of the invention is to provide an exceedingly simple, economical, and efficient switch actuating device and mounting for the general purpose described which is so constructed and arranged that the actuating device can be made of few simple parts and, therefore, sturdy, and which can be readily adapted to any suitable switch. 45 preferably a snap switch, wherein the active element of the switch resiliently remains in a position where thrown until intentionally actuated to throw to its opposite position.

A further object of the invention is to 50 produce an exceedingly sturdy and durable

construction well adapted to withstand the hard usage to which a foot actuated switch device is put.

The invention consists in the combination and arrangement of parts shown in the drawings and described in the specification, and is pointed out in the appended claims.

As shown in the drawings;

Figure 1 is a perspective view of a vacuum cleaning machine equipped with a switch 55 mounting embodying my invention.

Figure 2 is a vertical section of the switch and switch mounting therefor, showing the fixed casing enclosing it to constitute the switch unit.

Figure 3 is a bottom plan view of the parts shown in Figure 2.

Figure 4 is an enlarged vertical sectional view of the switch and switch mounting removed from associated parts.

Figure 5 is a perspective view of a frame 70 for carrying the snap switch mechanism and mounting from the fixed part of the machine or apparatus.

Figure 6 is a top plan view of the switch 75 mechanism and mounting.

Figure 7 is an inner side elevation thereof.

Figure 8 is a section on the line 8—8 of Figure 6.

Figure 9 is a fragmentary section on the 80 line 9—9 of Figure 8.

In the drawings, 10 designates the closure for the sweeper mechanism, 11 the usual motor and suction fan casing, 12 the outlet of the suction fan, and 13 the dirt receiving 85 bag connected to said outlet. 14 designates the usual handle connected by the forked arms 15 to the mechanism in any suitable manner. Said mechanism is supported partially on wheels 16, one of which is shown 90 in Figure 1.

18 designates, as a whole, my novel switch mechanism mounting shown in place in Figure 1. In said figure the switch and mounting are shown without the usual cover 95 or shield 19, a portion of which latter is shown in Figure 2. 20 designates the actuator of the switch mechanism which has the form of a lever, and in its adaptation to a vacuum cleaner, is adapted to swing in a 100 vertical plane.

The switch mechanism is fixedly supported, as herein shown, on a flange 21 of the motor and suction fan casing 11 through the means hereinafter described. The elements 110

of the switch mechanism and mounting are supported on a base or block 22 made of suitable insulating material, and suitably recessed and shaped to receive and support the 5 various parts of the mechanism, and, as shown, is concavely curved to fit against the exterior of the motor casing 11.

The switch mechanism per se may be of any known form of that type of switch which, 10 when actuated in one direction, as to close the switch, remains in such position until its actuator is actuated to open the switch, where it remains until it is again intentionally closed, the actuator lever always 15 returning to neutral after each throw of the switch. The switch mechanism can be principally located in a central recess 23 of the base 22 so that it will be amply protected from breakage. The switch mechanism may 20 include a U-shaped switch blade 24 which, when in the position shown in Figures 6 and 7, closes the circuit between contacts 25, 26, the latter of which is electrically connected to one side of the operating circuit through 25 a binding screw 28 suitably fastened to the base by a plate 29. The other contact 26 is electrically connected to one terminal of a pair of terminals (30, 31) that are adapted to be bridged by a twin contact plug 32 of 30 known form; one of which terminals, the terminal 31, carries a binding screw 33 for the conductor at one side of the circuit. The terminals 31, 32 are fixed to the insulating block by the screws 34, 35, respectively, 35 (Figures 6 and 8).

As herein shown, the arms of the U-shaped switch blade 24 are pivoted to external projections 40 carried by the opposite sides of a fixed box-like frame 41 that is provided 40 at its upper front and rear sides with ledges 42, 42 and are formed below said ledges on the rear edges of the walls with hook-like projections 43. 44 designates a U-shaped oscillatory switch blade actuating member, 45 the bottom 44' of which is pierced to receive the upper headed end of a link 47 that extends through a large opening in the bottom wall 48 of the fixed frame 41. The lower end of the link is loosely connected to 50 the actuating lever 20 by having an eye portion that extends through an opening 49 in said lever and is loosely anchored to the lever by a cross member, as the cotter pin 55. The upper free ends of said switch blade 55 actuating frame 44 are centrally pivoted at 52 to the upper or free ends of the arms 53 of a U-shaped switch blade controller and locking member, the bottom or closed portion 54 of which is connected by a spiral con- 60 tractile spring 55 with an eye 56 at the closed end of the switch blade. Said arms 53 are formed with horns 53' adapted alternately to engage over the fixed ledges 42 to lock the blade in given position.

When downward pull is exerted on the 65 link 47, through foot pressure on the actuator lever, the actuating frame 44 is depressed, thereby depressing the controller member and effecting stress on the spring 55, which operates, when the pivot points 70 52 pass the plane of the spring, to quickly throw the blade to one extreme of its movement and to simultaneously throw the controller member in the opposite direction to engage one of the horns 53' with the then 75 adjacent fixed ledge 42, as shown in Figure 4. When foot pressure is released on the actuator lever 20, the spring 55 serves to bring said lever 20 to normal, in readiness for throwing the switch blade and locking 80 it in its opposite position.

The snap switch mechanism described, or other known switch mechanism, is supported on the base of the block 22 by a frame designated as a whole by 57 (Figures 2, 3, 4, and 85 5), which is composed of two side arms 58, 58 arranged in general relatively oblique planes, a top cross member 59 that is provided with openings 60, and lower obliquely, outwardly directed supporting foot members 90 that are provided at their outer ends with apertures 62, through which extend screws 63, 63' by which the said mounting frame is fixed to a support. This supporting frame may be termed an adapter frame in 95 that it adapts the snap switch movement to the machine or device in connection with which the switch is to be used. The said side and foot members are embedded in suitable depressions in the insulating block 100 and the foot members are attached to the base 21. The said screw 63 closely fits within a bushing 64 in said opening and the lower end of the bushing 64 may extend through its foot member and be upset there- 105 under and also upset below the head of its screw, as shown in Figure 9. The threaded lower end of the screw 63 extends beyond said lower upset end of the bushing for threaded engagement with opening in the 110 flange 21, before mentioned. The fixed frame 41 of the switch movement can be fixed to the cross member 59 of the frame 57 by means of the screws 64', as shown in Figures 2 and 4, to thereby solidly fasten 115 the switch and mounting on the insulating mounting base.

The said actuating lever is shown as made of sheet metal. Its inner end 67, beyond the opening 49, is turned sharply upwardly 120 to form a fulcrum member that is disposed between the fixed frame 41 of the switch and the fixed motor shell 11. The said inner upstanding end of the actuator lever is formed with terminal bearing teeth 65 which 125 engage the adjacent cylindric wall of the shell 11, as shown in Figures 2 and 4, and the teeth or lugs 43 of said fixed frame enter

the spaces 65' between said teeth 65 (Figure 7).

- The construction described performs two functions; that of fulcruming the upstanding end of the actuator lever on the projections 43 of the fixed frame 41, and the bearing of the teeth 65 with a fixed part of the device, as the shell wall 11, serves to hold the notched fulcrum portion of said lever engaged with the fulcrum projections 43. Moreover, said projections extending into the notches between the laterally spaced teeth 43; avoids also sidewise displacement of the fulcrum end of the said lever.
- 15 In addition to the fastening means described, some of which have other fastening functions, as well as means to fasten the insulating base to the machine, the said base may be provided with other openings to receive fastening means sufficient to hold the insulating base firmly in place.

The construction described produces a very simple and economical means of mounting the actuating lever of an electrical switch, and especially a snap switch, and the arrangement is such that the fulcrum point for the lever is maintained in a very simple way, as by engagement of the lever terminal with an abutment which, in this instance, constitutes the wall of the shell 11. The actuator lever, therefore, is normally suspended between the link 47 and the point of contact of the lever with the abutment, or shell 11, so as to be in position to be freely moved downwardly about the under edges of the projections 43, as a fulcrum, to actuate the switch, and to be free to be swung upwardly to neutral position, when actuating pressure is released from the lever, by the spring 55.

The supporting frame 57 constitutes a very convenient and economical means to rigidly support the switch mechanism, of whatever kind used, on the base 22, so as to thereby provide an exceedingly sturdy switch mounting for such uses as herein illustrated and in other adaptations where the device as a whole is subjected in use to shocks and jars and to operating vibrations.

I claim as my invention:

1. A switch mechanism and mounting for the purpose set forth comprising a snap switch unit embracing a switch blade which is alternately movable to and locked at the terminals of its throw, of a one-way actuator lever loosely connected to a movable part of the snap switch unit and loosely fulcrumed on a fixed part of said unit.

2. A switch mechanism and mounting for the purpose set forth comprising a snap switch unit, a one-way movement actuator lever loosely connected to a movable part of the unit and loosely fulcrumed on a fixed part of said unit and an insulating base formed to receive and protect said unit and

having below the unit a front and rear through-opening through which said lever extends.

3. A switch mounting comprising, the combination with a snap action switch and a frame for supporting the same, of a one-way operating lever loosely connected to and suspended from an operative part of said switch and fulcrumed on a fixed part of the switch frame.

4. A switch mounting comprising, the combination with a snap action switch and a fixed frame for supporting the switch, of a lever loosely connected intermediate its ends to an operative part of the snap action switch and fulcrumed on a fixed part of said fixed frame, and formed terminally with means to maintain the lever fulcrumed on the switch frame.

5. A switch mounting comprising, the combination with a snap action switch and a fixed frame for supporting the switch, of a lever loosely connected intermediate its ends to an operative part of the snap action switch, and fixed, laterally spaced fulcrum elements on said frame, said lever being terminally formed inwardly beyond its said connection with teeth to enter between said fulcrum elements.

6. A switch mounting embracing, the combination with a snap action switch unit and its fixed frame, of a one-way actuator lever therefor extending beneath said frame and having an upturned terminal adapted for fulcrum engagement with a portion of said fixed frame and adapted for engagement with a relatively fixed abutment to hold the fulcrum parts engaged.

7. A switch mounting embracing, the combination with a snap action switch unit and its fixed frame, of a one-way actuator lever therefor extending beneath said frame and having an upturned terminal adapted for fulcrum engagement with a portion of said fixed frame and adapted for engagement with a relatively fixed abutment to hold the fulcrum parts engaged, and an adapter frame for supporting the switch unit on a machine and to constitute a guide for the actuator lever.

8. The combination with a switch movement complete with switch actuating mechanism and its own fixed frame, of an actuator lever extending beneath said frame and provided rearwardly beyond said frame with an upturned part that is fulcrumed to a fixed part of the switch frame, said lever being loosely connected between said upturned part and the outer end of the lever with a movable member of the switch movement.

9. The combination with a switch movement complete with switch actuating mechanism and its own unitary frame, of an actuating lever extending beneath the said

frame and provided with a rearward, upturned fulcrum terminal for engagement with fulcrum elements on said frame, and a link connection between said lever and a 5 movable switch element, intermediate the upturned end of the lever and its free swinging end.

10. In combination with a snap action switch movement having as a unitary part thereof a fixed frame, of a U-shaped adapter support having means by which it is connected to said frame and provided with means for attaching it rigidly to a device in connection with which the switch is to be 15 used, and an actuating lever having a swinging portion which extends between the arms of the U-shaped adapter support and provided with a rear, upturned part that is adapted for loose fulcrum engagement with 20 a fixed part of the switch frame, and is adapted to be engaged with an abutment which bears a fixed relation to the said switch frame to hold the parts in fulcrum relation, said lever having link connection 25 between its ends with a movable part of the snap action switch.

11. In combination with a snap switch movement having as a unitary part thereof a fixed frame, of a U-shaped adapter support having means by which it is connected to said frame and provided with means for attaching it rigidly to a device in connection with which the switch is used, and an actuating lever having a swinging portion which 30

extends between the arms of the U-shaped 35 support, said switch frame being provided with a rearwardly directed fulcrum member in fixed relation to an abutment on said device, and means affording loose connection between the ends of said lever and a movable part of the snap switch action, the lever being provided beyond said connection with an upturned fulcrum portion loosely connected with the fulcrum member of the 40 switch frame and adapted for terminal contact with said abutment. 45

12. In combination with a switch action, and an insulating base carved to form a rearwardly opening recess to receive the switch action, of a U-shaped adapter element for supporting said switch action having means for connecting its closed portion with a fixed part of the switch, and with its parallel arms lying along the side walls of said recess and provided with outstanding 50 foot portions which are secured to the bottom of said base, and a one-way actuator lever extending between said arms and loosely connected between its ends to an operable part of the switch action and having 55 a rearward upstanding part beyond said connection for fulcrum engagement with the switch frame.

In witness whereof I claim the foregoing as my invention, I hereunto append my signature this 11th day of December, 1920. 60 65

ERNST G. K. ANDERSON.
